UNITED STATES PATENT OFFICE.

PAUL SCHUYLER VAN BLOEM, OF HEMPSTEAD, NEW YORK, ASSIGNOR TO THE VIKING PRODUCTS CORPORATION, OF NEW YORK, N. Y., A CORPORATION OF NEW YORK.

SIGN.

Application filed November 24, 1922, Serial No. 603,011. Renewed January 19, 1926.

One of the main objects of this invention is the provision of a sign or signal plate, of translucent glass or other material which will permit the passage of light rays, having deeply impressed characters in its rear or light-receiving face, the said characters being in reverse and readable through the front face of the plate.

Another important object is to so form the sign plate that the walls of the impressed characters will be so shaped and disposed as to cause the light rays entering the impressions to be transmitted through the plate in a manner to give the illusion of raised characters on the front face of the plate.

The sign or signal plate is shown in a casing, and receiving illumination upon its rear face, but a sign of this character may be used effectively in daylight, or other general illumination, and independently of the casing and lamp.

In the drawings:

Fig. 1 is a front elevation of a signal with the plate mounted therein and indicates the illusion of relief characters upon the front face of the plate;

Fig. 2 is a vertical section taken through the signal on the line 2—2 of Fig. 1;

Fig. 3 is a fragmentary view of the rear face of the signal plate;

Fig. 4 a greatly enlarged detail section taken through the plate on the line 4—4 of Fig. 1 showing the form of one of the depressions and its effect upon the light rays cast therein;

Fig. 5 a similar view of a slight modification; and

Fig. 6 a view similar to Fig. 4 showing coloring or opaque matter applied to the bottom of the depression.

Referring to the parts, 1 designates the improved sign or signal plate. The plate 1 is made of transparent or translucent glass, or other suitable material which will permit the passage of light rays. The reverse face of the plate 1 is formed with a series of deeply impressed characters C, the said characters being in reverse as shown in Fig. 3 and readable through the front face of the plate as indicated in Fig. 1. In the present showing the plate 1 is adapted for use as an elevator signal and the impressed characters are the letters of the word "Down". The plate is larger than the over-

all dimensions of the impressed characters in order to secure a general illumination of that part of the plate surrounding the characters. The sign casing C' is provided, preferably, with a rear reflecting wall W. 60 A lamp L is suitably located and mounted within the casing to properly illuminate the plate. It will, of course, be understood that the lamp and signal plate could be mounted in other ways than the one shown. 65

Referring to Figs. 1 to 4 inclusive, the signal plate 1 has a substantially flat front face 2 and a rear or light-receiving face 3. The face 3 is formed with depressions 4 which conform in outline to the character 70 to be displayed through the front face of the plate. In the present instance the depressions form the strokes of a letter. Each of the said depressions is formed with side walls 5 which in cross section are straight 75 as shown in Fig. 4 and are substantially perpendicular to the plate face 3. The bottom 6 of the depression curves inwardly at the sides as shown at 7 and merges with the side walls 5. The side walls 5 are of 80 material depth particularly with relation to the width of the letter stroke, and this depth of the side walls and their substantial perpendicularity to the plate face together with the curves 7 are important factors in accomplishing one of the objects of the invention, 85 that is, to produce the illusion of a character in relief upon the front face of the plate.

The effect of the light rays which are directed into the depressions 4, as illustrated in Fig. 4, is as follows, assuming that the signal is viewed from directly in front: the ray a which passes through the center of the depression will not be refracted but will be transmitted straight to the eye of 90 the observer. The rays b at either side of a are caused to be refracted or diffused away from the eye of the observer, toward the right and left, by the curves 7. The oblique rays c will also be refracted or diffused away from the eye of the observer toward the right and left. Owing to the substantial perpendicularity of the walls 5 to the rear face of the plate most of the rays d incident thereon will be beyond the critical angle, or the angle at which they would penetrate the plate, and will therefore be totally reflected to the bottom of the depression, from whence they will be refracted and transmitted in the direc- 110

tion of the observer. Owing to the fact that the rays *a* and *d* are concentrated and forwardly directed and that the rays *b* and *c* strike the curves 7 and are caused to diverge away from the eye of the observer, the character will be brilliantly illuminated at the center and will shade away at the sides and cause the forwardly bulged appearance of the character as indicated in Fig. 1. The side walls 5 of the depressions diverge slightly to permit the withdrawal of the mold used in forming the depressions. This divergence of the walls tends to increase the shaded effect at the edge of the character when viewed from the front.

When the signal is viewed obliquely as from the direction indicated by the right hand arrow in Fig. 4, the rays such as *c* and *b* which are cast upon the curve 7 are directed toward the observer while the rays falling upon the bottom 6 and the nearer side wall 5 are directed away from the observer thus causing the character to appear as an outstanding perspective with a high-light at the corner due to the rays coming through the curve 7 and with the bottom 6 and side walls 5 of the depression shading off from either side of the high light.

Fig. 5 shows a slight modification, the bottom of the depression in this case being uniformly curved. This form will increase the diffusion of the rays and will produce a character somewhat different in appearance from the form shown in Fig. 4.

In Fig. 6, the bottom 6 of the depression 4 is shown as provided with either a colored or an opaque coating 9 to produce a desired ornamental effect. The coating 9 may be applied to only the center of the bottom 40 leaving the curves 7 uncoated so as not to diminish their effect.

It will be seen that a simple, easily manufactured sign or signal and one that is also beautiful and effective, is provided. A signal of this character which permits the light to pass through the entire area of the plate is particularly effective as it makes a more striking effect and will attract more attention than if merely the characters were illuminated. The form shown in Fig. 1 may also be kept clean and bright with a minimum of effort as there is no place for dust to lodge on the front face as is the case with projecting characters.

A sign of this character is effective even when used independently, without the special illumination shown in Fig. 2. When unprovided with special illumination the sign will share in the general illumination, either daylight or artificial, of its surroundings, and if both front and rear faces receive illumination the effect will be the same as indicated in Fig. 1 in which the characters have a shaded outline, while if the sign is disposed against a dark background and

receives most of its illumination from the front, the effect is reversed, the outlines of the characters appear bright while the centers of the characters and the rest of the sign appear dark.

70

What I claim is:

1. A sign plate of material adapted to permit the passage of light rays formed in its rear or light-receiving face with a depression conforming in outline to a sign character, the said depression having a bottom, side walls so disposed as to reflect most of the light rays received thereon upon the bottom, and surfaces at the juncture of the side walls and the bottom so disposed as to cause light rays cast thereon to be refracted away from the center.

75

2. A sign plate of material adapted to permit the passage of light rays formed in its rear or light-receiving face with a depression conforming in outline to a sign character, the said depression being formed with a bottom adapted to transmit directly the light rays which fall centrally and normally thereon and to refract away from the center rays which fall upon the bottom at either side of its center.

80

3. A sign plate of material adapted to permit the passage of light rays formed in its rear or light-receiving face with a depression conforming in outline to a sign character the said depression having a bottom through which the light is transmitted, side walls of material depth substantially perpendicular to the rear face of the plate, and adapted to reflect light rays to the bottom, and surfaces connecting the bottom and the side walls adapted to cause the light rays falling thereon to be refracted away from the center.

85

4. A sign plate of material adapted to permit the passage of light rays formed in its rear or light-receiving face with a depression conforming in outline to a sign character the said depression having side walls of material depth and substantially perpendicular to the rear face of the plate, and a bottom curved rearwardly at the sides to merge with the said side walls.

90

5. A sign plate of material adapted to permit the passage of light rays formed in its reverse face with a depression conforming in outline to a sign character the said depression having a bottom, side walls disposed to reflect light rays upon the bottom and a coating of colored matter applied to the bottom, the said coating terminating short of the side walls.

100

6. A sign plate of material adapted to permit the passage of light rays formed in its rear or light-receiving face with a deep character impression, the said impression having a concave bottom and side walls substantially perpendicular to the rear face of the plate.

105

110

115

120

125

130

7. A sign plate of material adapted to permit the passage of light rays and formed in its rear or light-receiving face with a depression conforming in outline to a sign character, the said depression having light-reflecting side walls of material depth and substantially perpendicular to the rear or light-receiving face of the plate, the said

plate being larger than the over-all dimensions of the sign character and admitting ¹⁰ light through the character and through its area surrounding the character.

In testimony whereof I hereunto affix my signature.

PAUL SCHUYLER VAN BLOEM.
